UNITED STATES PATENT OFFICE

JOHN B. JAQUA, OF ALHAMBRA, CALIFORNIA

OIL-CRACKING PROCESS

Application filed November 26, 1926. Serial No. 150,762.

Although my present invention is entitled, somewhat broadly, as referring to an oil cracking process, it should be understood that this invention relates more particularly to a process in which mineral oil is cracked mainly or entirely while in the liquid state or phase; and the most unique feature of my invention may be the technique by which I impart heat to crude or other oil, for cracking or analogous effect.

By the use of a novel process and apparatus which it is an object of this invention to provide, I avoid or reduce to a minimum such local overheating of pipes, or the like, as tends to produce carbon deposits therein; I preferably add a non-aqueous heat-transferring fluid in increments, at successive stages of conversion, maintaining a temperature for a predetermined time and obviating the use of an unduly high initial temperature; and I maintain in heating and cracking coils a velocity of flow sufficient to carry forward such carbon as may inevitably result from the heating and/or cracking operations effected therein.

As pertinent to the main problems which it is an object of my invention to solve, I quote the following from a work entitled "Gasoline and Other Motor Fuels," by Ellis and Meigs (Van Nostrand Company, 1921, page 431): "Many investigators have realized that overheating an oil has a tendency to decompose it into fixed gases and carbon. For example, by forcing oil through red hot pipes it is possible almost completely to break the oil up into fixed carbon and gas, without the formation of any naphtha, if the vapors remain long enough in contact with the heated surfaces. With direct firing, overheating is sometimes difficult to avoid. With this in view, many processes have been proposed for maintaining a more uniform temperature by means of fused baths of metals or salts."

Although some of the results of my invention may be obtained by using fused baths of metals or salts, it is an object of my invention to gain the essential advantages thereof, and additional advantages, by simpler and/or superior means; and, in preferred embodiments of my invention, using

a comparatively stable oil (such as a thermolized gas oil obtainable as "bottoms") for a heat-transferring effect, and heating this medium to a temperature somewhat above that desired to effect an endothermic reaction of the raw mineral oil (such as a cracking reaction) I deliver the mentioned heat-transferring fluid, or its equivalent, in the form of separate small streams thereof, fed at successive points, into an advancing stream of the oil within which the mentioned reaction is to be produced,—the latter oil being preferably brought, in advance of the mentioned admixture, to a temperature only slightly below that which may be prerequisite to the desired reaction, and the mentioned additions being preferably so proportioned and so spaced, relatively to the dimensions and the rate of advance of the treated oil, as to maintain a desired reacting temperature or temperatures therein for a predetermined period or periods.

Other objects of my invention, including the use of preferred means and methods for obtaining the desired volatile products from the resultant stream, and the use of novel means and methods permitting thermolized and relatively stable oil fractions to be repeatedly returned (and used as "cycle stock") in such manner that they may not only serve for a heat-transferring effect but may themselves gradually become decomposed into lighter products, and including also novel features of interconnection and organization of apparatus as herein described, may be best appreciated from the following description of illustrative embodiments of my invention, taken in connection with the appended claims and the accompanying drawings, in which—

The figure may be referred to as an entirely diagrammatic elevational view, with parts broken away, of an apparatus suitable for use in the practice of my invention.

Referring to the illustrated embodiment of my invention, I show a cracking coil 11 as comprising a series of separate sections 11^a, 11^b, 11^c, 11^d and 11^e; this coil being preferably entirely unprovided with means for a direct heating thereof, and being shown as

provided with a supply pipe 12, for the mineral oil in which a cracking or other endothermic reaction is desired.

Although it is an object of my invention, as indicated above, to obviate, so far as possible, the deposition of carbon or heavy residues within cracking apparatus, in view of the fact that, generally speaking, oils may be brought near to their cracking temperatures without such deposition, I may interpose in the supply pipe 12, or its equivalent, a preliminary or primary heater of any preferred type, such as that shown at 13 as comprising a coil of pipe exposed to direct or indirect heating by a flame 14,—oil being fed thereto by means such as a pump 15, assumed to operate at a rate consistent with the opening of valves such as are indicated at 16 and 17.

After the oil is fed through the preliminary heater 13 and therein heated, in the described manner or in an equivalent manner, to a temperature slightly below that which may be pre-requisite to a cracking or other desired physical or chemical effect, I prefer to add thereto the heat required for obtaining such effect by introducing, as by way of a manifold 18 and separately valved branch pipes 18^a, 18^b, 18^c, 18^d and 18^e, a liquid heat-transferring medium, such as a relatively stable oil, heated to a temperature slightly above that required to effect the desired physical and/or chemical change in the treated oil, as the same is introduced through the supply pipe 12 and advanced through coil 11; and the mentioned stable oil, or its equivalent, may accordingly be brought to the desired high temperature by means such as a so-called superheater or storage heater 19, shown as constructed similarly to the mentioned preliminary or primary heater 13 and as heated by a flame 20,—a coil comprised in the mentioned superheater being shown as connected with the manifold 18 by a valved pipe 21.

The cracking coil 11 being shown as provided with an outlet 22, in which I prefer to interpose a pressure-reducing valve 23, said outlet may terminate, at an intermediate level, in a separator or in an interposed vaporizer 24,—this being shown as provided with a vapor outlet 25,—through which may pass such volatile products as are produced by the mentioned cracking reaction within the coil 11; and thermolyzed residuum and/or heavy intermediate fractions may be withdrawn through a bottom outlet 26 and/or through an additional valved outlet, such as that shown at 27 as connected with said vaporizer at an intermediate level.

Although I show both of the outlets 26 and 27 as connected with a return pipe 28 by which, upon the operation of a pump 29, a residue delivered through either of said pipes, or a mixture of such residues, may be returned through a pipe 30 to the superheater 19, I show said outlet pipes as also communi-

cating, by valved branches 31 and 32, with a pipe 33—shown as valved at 34 in a manner permitting the withdrawal of said residue or any comparatively non-volatile product; but I prefer ordinarily to supplement the action of the so-called vaporizer 24 by the use of an additional element, somewhat similar in construction connection, such as separator 35. This is shown as connected, at an intermediate level, with the vapor pipe 25, and as provided with a pressure-reducing valve 36 in what I may term a final vapor outlet 37 for desired distillates.

Assuming that the vaporizer 24 and the separator 35 are to be operated at different temperatures and pressures, and in order to accomplish both a condensing effect in these elements and an initial heating of raw oil to be fed by the pump 15, or its equivalent, I may carry the raw oil pipe 12, or its equivalent, through either or both of the mentioned elements 24 and 35, as by providing coils 38 and 39 therein (bubble plates being optionally interposed, as at 40, in both or one of said elements); and I may also interpose in the vapor pipe 25, or its equivalent, a pressure-reducing valve 41.

The separator 35, or its equivalent, being intended, when thus employed, to receive only such hydrocarbons as have passed through the vapor pipe 25, I need ordinarily make, in connection with said separator, no provision for the withdrawal of such heavy residues as may be discharged from the vaporizer 24, past the valve 34 in pipe 33; but I nevertheless show the said separator as provided with a bottom outlet 42 (communicating both directly and indirectly with the mentioned return pipe 28) and also with a lateral outlet 43. The outlet 43 may deliver any desired intermediate fraction, by way of a valved pipe 34' (with which the mentioned pipe 33, from vaporizer 24 may be connected by a valved lateral 44) into a tank not shown; and the outlet 42 is shown as provided with a valved branch 42', leading to a storage tank 45. The later is shown as connected by an outlet pipe 46 (in which a pump 47 may be interposed) with the mentioned return pipe 28,—this arrangement adapting said tank to serve for a make-up purpose hereinafter referred to.

In the ordinary use of an apparatus of the general character described, a raw material such as a crude or topped oil (assumed to contain little or nothing of a gasoline fraction) may be continuously admitted into the inlet end 12^a of the pipe 12, or its equivalent, receiving heat and serving for a cooling effect during its passage through the coils 38 and 39, and being heated in the preliminary or primary heater 13 to a temperature such as 700°-800° F., without any appreciable cracking effect; the superheater or storage heater 19 may be maintained at a temperature

(such as 900°-1000° F.) slightly above that required for a cracking or other endothermic action upon the oil fed through the pipe 12, or its equivalent; and the valved inlets 5 18^a-18^e may be so spaced and adjusted as to maintain throughout the cracking coil 11, notwithstanding an absorption of heat therein, a desired temperature gradient or a substantially uniform temperature, such 10 as a temperature between 800° and 900° F., as by admitting separate increments of the heating medium in successive small portions suitably spaced along the course of the stream of oil entering said cracking coil by way of 15 pipe 12. For example, a relatively heavy and undecomposable, stable re-circulated oil, having a suitable fluidity and temperature, may be delivered from the manifold 18 through the mentioned valved inlets in such 20 quantities as neither to occasion an excessive rise nor to permit an excessive drop in the temperature of the treated oil with which said re-circulated oil may be admixed. For the purposes referred to, I may ordinarily 25 use about three parts of said re-circulated oil to one part of the treated oil.

The pipes employed in the cracking coil 11, although perhaps ordinarily reaching a total length such as 500-1500 feet, are intended 30 to have a diameter (as, a diameter of 6" to 12") assuring continuous flow therethrough; and the rate of said continuous flow may be such as to assure an advance of the resultant mixture at a rate such as one 35 or two feet per second, or at a rate assuring a maintenance of the desired temperature for a period such as 5-15 minutes, and obviating deposition of carbon,—about 200-300 lbs. pressure being maintained.

40 The mixture of raw oil and re-circulated thermolyzed oil (or other liquid employed as a medium for the transfer of heat) being preferably kept mainly or entirely in the liquid phase up to the time of its advance past the valve 23 or its entry into the vaporizer 24, an outlet pressure not exceeding about 50 pounds and a temperature such as 650° may be maintained in this element,—an outlet pressure not exceeding about 50 pounds, and 45 a temperature between about 400° and 550° F., being then appropriate to the separator 35, or its equivalent.

It will be obvious that the foregoing temperatures are mere approximations,—the 50 limits of variation tolerated being dependent not only upon the character of the raw oil treated but upon the specific product desired, and the described method being entirely suitable to use in the production of 55 either gasoline, or kerosene, or lubricating oils and capable of use not only with heavy and/or intermediate oil fractions of widely different types but also capable of use with other re-circulated heating mediums, such as 60 molten salts or metals; but my use of so-

called thermolyzed oil or other relatively stable oil or oil mixture as a heating medium has the important advantage that it not only favors production and separation of the desired products from the raw oil but incidentally augments the quantity of said products, by either a rapid or a gradual cracking of the heat-transferring medium itself,—although the temperatures maintained respectively in the preliminary heater 70 13 and the superheater 19, as related to the cracking temperatures of the respective oils circulated therethrough, may be, under the conditions described, such as to result in only a very slight or slow accumulation of carbon 75 therein or in the cracking coil 11.

At the time operations are begun, an oil suitable for use as a heat-transferring medium may be advanced from any convenient source (as, for example, from the storage 80 tank 45) to the superheater 19, simultaneously with the advance of raw oil, to be cracked, through the pipe 12; as soon as regular operation is under way, any desired proportion of the residual oils or bottoms which accumulate 85 in the lower portions of vaporizer 24 and/or separator 35 may be returned, by mentioned connections, through the pipe 28 and pump 29; and, in order to provide for either an automatic or a manual control of such 90 return, and also for varying the output of residuum or bottoms through the valved pipe 34 (which may lead to a fuel oil storage tank, not shown) and through the valved pipe 42 (communicating with the tank 45) I show the bottom outlet 26 and intermediate outlet 95 43 of the separator 35 as respectively provided not only with manual valves 48 and 48' but also with liquid-level-controlled automatic valves 50 and 51,—these latter being 100 adapted, even though the valves 48 and 48' be kept wide open, to maintain a predetermined level of oil in said vaporizer and in a part 105 of said separator respectively.

In case exclusive reliance were to be placed 110 upon the automatic valves 50 and 51, some of the mentioned pipes and/or valves might be dispensed with; but I consider it advantageous to provide all of the same, in order to permit reliance upon the manual valves 48 and/or 49 to control bottom outlets; in order to predetermine an upper limit of residuum or bottoms or intermediate fractions accumulating in the vaporizer and/or the separator; and in order to facilitate such variations in 115 the return flow of the heat-transferring medium through pipe 28 (compared with the delivery of residues or bottoms through pipe 34, and/or the delivery of an intermediate fraction through pipe 34' and/or with the accumulation of residues or bottoms in tank 45) as may be appropriate to the utilization of different types of raw oil or to the production of specific volatile products desired. 120 One thousand barrels of raw oil passed 125

through the cracking coil with (say) 3,000 barrels of a recirculated heavy intermediate oil may yield (say) 350 barrels of gasoline (via 37) 500 barrels of a lubricant or other intermediate oil (via 34') and about 150 barrels of fuel oil via 34; but it should be understood that the recirculated oil may be of either higher or lower gravity and specific heat than the raw oil that is cracked by transfer of heat therefrom.

It will be apparent from the foregoing that the storage tank 45 is properly referred to also as a make-up tank, for the reason that, after the running of a batch of comparatively heavy raw oil, an excess of thermolyzed residual and/or intermediate oils may either be disposed of (as fuel oil, or the like) or used as a recirculated heat-transferring medium during a subsequent running of a quantity of less heat-resistant oil.

By the described means, some 25% to 35% of the raw oil initially containing no appreciable quantity of gasoline may be converted into a product marketable as gasoline,—the conversion being presumably distributed between the successive sections of a cracking coil of the general character described; but I call attention not only to the high percentage of gasoline and/or kerosene recovery and to the controllability, versatility and simplicity of the described apparatus and method but also to the fact that said apparatus and method are such as to permit operation for long periods (amounting to months, as against days or weeks in the case of other types of apparatus currently employed) between shut-downs for purposes of cleaning out deposits of carbon, or the like.

Although I have herein described a single complete embodiment of my invention, including various optional features and suggesting alternative connections and modes of operation, it should be understood not only (1) that I place especial emphasis upon my use of recirculated, relatively stable oil, added in successive increments and at a high temperature to a stream of oil to be cracked thereby, and (2) that various features of my invention may be capable of independent use, but also (3) that numerous modifications of both my apparatus and my process might easily be devised, by those skilled in the arts to which this case relates, without involving the slightest departure from the spirit and scope of my invention, as the same is indicated above and in the following claims; but only in the "limiting" case will a total quantity of the heat-transferring oil be added at one time to the oil to be cracked.

6. I claim as my invention:

1. A method of cracking mineral oil which comprises: heating a fluent heat-transferring medium in the form of a relatively stable oil to a temperature above the temperature at which, under the given conditions of pres-

sure, the first-mentioned mineral oil may be cracked; and advancing said medium, while so heated, into direct contact with said first-mentioned mineral oil and thence, after a sufficient time interval to permit a cracking reaction, at the resultant temperature, into a region of less pressure, the heat in the relatively stable oil being such as to obviate other application of heat, subsequently to said contact, to said first-mentioned oil, for the desired cracking effect.

2. A method of cracking mineral oil which comprises: heating a fluent heat-transferring medium in the form of a relatively stable oil to a temperature above the temperature at which, under the given conditions of pressure, the first-mentioned mineral oil may be cracked; advancing said medium, while so heated, into direct contact with said mineral oil and, after a sufficient time to permit a cracking reaction at the resultant temperature, into a region of relatively less pressure; and taking off resultant vapors from said last-mentioned region,—the temperature of the relatively stable oil being such as to obviate other application of heat, subsequently to said contact, to said first-mentioned oil, for the desired cracking effect.

3. A method of cracking a mineral oil which comprises: heating a fluent heat-transfer medium to a temperature above the temperature at which, under the given conditions of pressure, the said mineral oil may be cracked; advancing said medium, while so heated, into direct contact with said mineral oil; advancing the mixture of said medium and said oil in a stream, then separating resultant vapors, and returning residues thereby obtained for use, in like manner, as a heat-transfer medium, in the cracking of an additional quantity of mineral oil.

4. A method of cracking a mineral oil which comprises: heating a heat-transferring medium, in the form of a heavy oil, to a temperature above that at which, under the given conditions of pressure, the said mineral oil may be cracked; advancing said medium in separate increments and while so heated, into a stream of said mineral oil; and taking off resultant vapors.

5. A method of cracking mineral oil which comprises: heating a stream of said mineral oil and a stream of a fluent heat-transferring medium, in the form of a relatively stable oil, respectively to a temperature below and to a temperature above the cracking temperature of said mineral oil; and commingling said streams during a continued advance thereof.

6. A method of cracking a mineral oil which comprises: heating a stream of said mineral oil and a stream of a fluent heat-transferring medium, in the form of a relatively stable oil, respectively to a temperature below and to a temperature above the crack-

ing temperature of said mineral oil; and commingling said streams by adding said medium to said oil, during a continued advance thereof, in successive increments and 5 at points spaced along said mineral oil stream.

7. A method of elevating a mineral oil, largely liquid, to a cracking temperature while minimizing the formation of undesired products therein which comprises: bringing into direct contact therewith, during continued advance, a body of a stable oil which contains sufficient heat to elevate said mineral oil to a cracking temperature,—the resultant 10 admixture being advanced, mainly still in liquid phase and without external application of heat thereto subsequently to the mentioned contact, toward a point of vaporization of lighter products at a less pressure.

20 8. A method of elevating a mineral oil to a cracking temperature while minimizing the formation of undesired products therein which comprises: bringing into direct contact therewith a body of a stable oil which contains sufficient heat to elevate said mineral oil to a cracking temperature by flowing one of said oils into a continuously advancing stream of the other of said oils, the heat in the relatively stable oil being sufficient, at the time of the mentioned contact, to produce a cracking temperature in the mineral oil, without subsequent external application of heat.

25 9. A method of elevating a mineral oil to a cracking temperature while minimizing the formation of undesired products therein which comprises: bringing into direct contact therewith a body of a stable oil which contains sufficient heat to elevate said mineral oil to a cracking temperature by flowing said stable oil into a stream of said mineral oil in separate increments added at successive 30 points along the course of said stream, said increments being so spaced and so proportioned as to maintain a desired temperature in said stream for a predetermined time.

35 10. A method of imparting to an oil that heat which is required to effect a desired endothermic reaction therein which comprises: heating another and more stable oil to a temperature above that prerequisite to the mentioned endothermic reaction; and thereafter directly admixing said oils, during 40 continued advance in generally concurrent flow and without subsequent application of heat, in proportions predetermined with reference to the thermal requirements of said reaction.

45 11. A method of the general character defined in claim 10 in which the second-mentioned oil is heated to a temperature but slightly above the mentioned prerequisite temperature.

50 12. A process of the general character defined in claim 10 in which the second-men-

tioned oil is an oil which is relatively insusceptible to the mentioned endothermic reaction.

13. A method of the general character defined in claim 10 in which the second-mentioned oil is an oil of higher specific heat than the first mentioned oil. 70

14. A method of the general character defined in claim 10 in which the second-mentioned oil contains residual fractions obtained by the separation of a desired product from a mixture previously produced in the manner set forth in said claim. 75

15. A method of the general character defined in claim 10 in which the desired temperature is maintained, for a predetermined period, by making a series of small additions of said second-mentioned oil at successive points along the course of a stream of said first-mentioned oil. 80

16. A process of the general character defined in claim 10 in which said oils are respectively heated, before they are brought into contact, to temperatures respectively below and above the cracking temperature of said first-mentioned oil, and in which a separation of desired products from a resultant mixture is effected by steps comprising a delivery of the same, at a diminished pressure, into a vaporizer. 90

17. In means for the cracking of mineral oils: a superheater; a cracking coil comprising separate consecutive sections; means for delivering a liquid heat-transferring medium from said superheater, and in separate small streams, into said sections; means for forcing the oil to be cracked into a first of said sections; means for separating vapors from a resultant mixture; and means for repeatedly returning a heavy residue, through said superheater, to serve as said heat-transferring medium in said cracking coil. 100

18. A method of cracking a mineral oil which comprises: heating a stream of a heat-transferring medium while out of contact with said mineral oil to a temperature above the temperature at which said mineral oil may be cracked; advancing said stream of heat-transferring medium while so heated into direct contact with a separately advancing stream of said mineral oil, to heat the latter during its advance and without subsequent application of external heat; separating resultant vapors from the residue fractionating the vapors; and employing at least a portion of bottoms from the vapor fractionation as said heat-transferring medium. 110

19. A method of cracking a mineral oil which comprises: heating a stream of a heat-transferring medium while out of contact with said mineral oil to a temperature above the temperature at which said mineral oil may be cracked; advancing said stream of heat-transferring medium while so heated into direct contact with a separately advanc- 115 120 125 130

ing stream of said mineral oil, to heat the latter during its advance and without subsequent application of external heat; separating resultant vapors from the residue; fractionating the vapors; and employing at least a portion of the resultant bottoms, together with at least a portion of said residue, as said heat-transferring medium.

In testimony whereof, I have hereunto set
10 my hand at Los Angeles, California, this
15th day of November, 1926.
